SAFETY RAZOR

Filed March 20, 1925

Inventor:

Alfred Schlüssler
by *Janisch*
Atty.

UNITED STATES PATENT OFFICE

ALFRED SCHLÜSSLER, OF BERLIN-NEUKOLLN, GERMANY

SAFETY RAZOR

Application filed March 20, 1925, Serial No. 17,061, and in Germany March 22, 1924.

With the known safety-razors with bent and adjustable blade this latter is pressed down onto the stationary lower clamping-plate by the rim-parts of the movable upper clamping-plate, said rim-parts engaging the blade near its cutting-edges and holding these latter in proper working position in which they contact closely with the said rim-parts.

10 Now, it is known that while the so-called pre-shaving is going on, especially in the case of strong growth of the beard or whiskers, an elastic blade is more agreeable than an inelastic one, and there have already been 15 devised safety-razors, in which the blade is fixed or clamped at places located more distant from the cutting-edges so that the blade-rims yield elastically in a certain slight measure during the shaving.

20 These razors are not suited, however, for the so-called smoothing or finishing shave as the blade, owing to its yieldingness, glides merely away over the hairs. A rigidly clamped blade is, in fact, more suited for 25 this last-mentioned operation.

My improved razor is distinguished, in general, by the feature that it answers all requirements above mentioned, and in particular the gist of the invention consists 30 therein that the upper clamping plate is provided either at only one of its two longitudinal rims, or at both, with channel-like recesses, by which the respective rim is provided with two edges, an outer one and an 35 inner one, the outer being more remote from the lower clamping plate than is the inner edge and the position of the two edges being such that when the upper clamping-plate is tightly drawn home against the lower one

40 the cutting-edge of the blade clamped in between the two plates does not contact with the outer edge of the upper clamping-plate but can yield relatively thereto in that there is a gap between that edge and the cutting 45 edge of the blade. But when the outer clamping-plate is moved a little away from the lower one, the blade which had been bent

circularly between the curved adjacent surfaces of the two plates follows at its rims the outer plate until these rims touch the

outer edges of the upper plate, in consequence whereof the gaps are closed and the blade rims cannot yield outwardly. This takes place either at only one longitudinal rim of the outer clamping-plate or at both rims thereof if both are provided with the channel-like recess mentioned in the first part of this paragraph.

There are also a few more characteristic features as regards the clamping-plates; 60 they are dealt with hereinafter.

My invention is illustrated diagrammatically and by way of example in the accompanying drawings, in which Figure 1 is a side-view of the head of a safety-razor constructed according to this invention, the figure being drawn to a greatly enlarged scale; and the handle-parts which are shown in axial section being broken off; Figure 2 is a similar view, the upper clamping-plate 70 and the blade being shown in another position and the handle-parts being entirely removed; Figure 3 is a cross-section through a modified upper clamping-plate, and Figure 4 is a side-view of a modification of the 75 entire razor, chiefly, however, of the lower clamping-plate.

Referring to Figs. 1 and 2, the upper clamping-plate 1 is pressed onto the blade 4 and the lower clamping-plate 9 in known manner by suitably devised threaded members either of the kind shown in Fig. 1 or of any other kind. I abstain from entering into details in this respect as these members do not form part of the invention. The outer surface of the plate 9 and the inner surface of the plate 1 are bent circularly in known manner, as is, of course, also the blade when being clamped in.

In the example in question the plate 1 is provided at either of its longitudinal edges with a channel-like recess 1^a whereby an inner edge 2 and an outer edge 3 are formed. The edge 2 contacts always with the blade 4, but the edge 3 only when the plate 1 has been moved away a little from the plate 9, as in Fig. 2. In Fig. 1 the channel or recess 1^a forms a gap between the rim of the plate 1 and the rim of the blade, in consequence whereof the blade-rim, or the cutting-edge 100

4^a respectively, can yield outwardly, but when the plate 1 is moved a little off the plate 9 the blade rim approaches the plate-rim, contacts therewith, and is supported by it, as illustrated in Fig. 2. This is, thus, that position of the blade which is suited for the second shaving in which the cutting-edge shall not yield, whereas the other position (Fig. 1) is that suited for the first shaving.

10 In the example illustrated in Figs. 1 and 2 one side of the plate 9 is provided with a channel 6, the outer edge 5 of which lies below the cutting-edge of the blade, or, more precisely, behind, but near it. In other words: the blade-rim covers that channel completely. This constructional form of the razor affords that advantage over the other form (lefthand half of Fig. 1) that the cut-off particles of hair do not gather below the 15 blade-rim and impede its elasticity.

20 In the modification shown in Fig. 3 the two edges 2 and 3 of, or at, the upper clamping plate 1 are formed by a separate plate 8. This constructional form disclosed the possibility of changing existing safety-razors into such with two edges 2 and 3 according to this invention.

25 In the second modification, Fig. 4, the upper clamping-plate is provided with a large lower recess 12, and the lower clamping-plate with a large upper recess 14, and the blade is held merely between ledges 10 and 15, of which the projections 10 are practically of 30 angular cross-section with rounded-off supporting-edges for the blade, whereas the projections 15 are practically flat; their faces lie obliquely with respect to the axis of the razor and their position relatively to one another is such that the blade is curved circularly as 35 in Fig. 1. The elasticity of the blade-rims, or of the cutting-edges respectively, in the direction to the edges 3 is in this constructional form greater than in Fig. 1, because also the middle part of the blade can give 40 way (in the direction to the handle). In all other respects matters are as described with respect to the other constructional forms 45 shown and described.

50 The rims of the lower clamping-plate 7 are, of course, provided in known manner with many parallel incisions whereby each rim is turned into a kind of comb. Each incision communicates at its inner end with the channel 6 (Figs. 1 and 2). But as regards Fig. 4, matters are in this respect otherwise, in that the parallel incisions extend obliquely; in other words: each incision 55 forms a narrow channel having an oblique bottom 11 (Fig. 4) terminating at the lower-most point 13 where there now exists a continuous edge by which the superfluous soap-froth is removed from the skin. Besides, the cut-off particles of hair get easily into the recess 14 through the gaps between the 60 comb-forming members at the inner ends 65

thereof. The pure soap-froth removed by, or at, the edge 13 which is free from hair-particles may be used over again.

Generally the lefthand and the righthand half of the razor will be made alike, but if 70 desired or for certain cases they may be different one being then of the known usual construction, the other of the improved construction, either according to Figs. 1 and 2, or according to Fig. 4.

75 The provision that the cutting-edge of the blade extends over the channel 6, i. e. outwards beyond the point 5, is important for such cases where the skin of the man who will shave himself has pimples, scars, or the like. If the cutting edge of the blade would terminate inwards of the point 5 the skin would be exposed to the danger of being hurt at its projecting parts. On the other hand, the cutting-edge should not extend 80 too far outwards beyond the point 5 because then hair-particles can be clamped fast between the blade-rim and the points or parts 85 of the comb-teeth.

90 It is not indispensably requisite that the edge 2 forms a kind of ledge between the concave face of the upper clamping-plate and the recess 1^a; it is, in general, sufficient if it is actually a mere edge between that face and the slightly curved or, perhaps, even plain surface extending from it to the edge 3.

95 I claim:

1. A safety razor comprising in combination an elastic blade, a lower clamping plate 100 having a convex upper surface, an upper clamping plate having a concave lower surface concentric with said convex surface, the concave surface of said upper clamping plate being undercut along its edges so that two 105 contact strips are formed along each edge, the outer strip extending to a greater radial distance from the centre about which said surfaces are curved, than the inner strip.

2. A safety razor comprising in combination an elastic blade, a lower clamping plate having a convex upper surface, an upper clamping plate having a concave lower surface concentric with said convex surface, the concave surface of said upper clamping plate being undercut along its edges so that two contact strips are formed along each edge, the outer strip extending to a greater radial distance from the centre 110 about which said surfaces are curved, than the inner strip and said upper and lower surfaces being partly cut away at the rear 115 of said inner strips so as to constitute a pair of parallel supporting faces on both sides of said blade.

120 In testimony whereof I affix my signature.

125 ALFRED SCHLÜSSLER.
